PACKAGE OPENER

Hamilton Grinnell Disbrow, Madison, N. J., assignor to International Safety Razor Corporation, Bloomfield, N. J., a corporation of New Jersey

Application June 27, 1939, Serial No. 281,317

1 Claim. (Cl. 30—2)

This invention relates to an improved package opener, particularly to a package opener adapted to be used in removing the top, bottom, or side panel of a package by cutting around the edges thereof.

It is an object of the above invention to provide an improved package opener of the above character in which the cutting implement may be a razor blade and particularly a single edge type of razor blade having a backing strip thereon.

A further object is the provision of a package opener of improved safe construction which substantially reduces the danger of accidental injury and in which the cutting implement is readily adjustable so that the cutting edge thereof may be exposed to varying degrees or may be fully retracted and encased within the handle portion of the device.

Another object is the provision of an improved package opener adapted to use a single edge razor blade as the cutting implement; in which the blade may be conveniently inserted or replaced; and in which the razor blade, while being readily adjustable, is firmly held in any desired adjusted position.

It is a further object of the invention to provide an improved package opener of the above character in which the top, bottom, or side panels of the package can be readily removed without injuring the contents of the package.

In the accompanying drawing—

Fig. 1 is a perspective view of a package opener embodying my invention;

Fig. 2 is a longitudinal sectional view in the direction of the arrows on the line 2—2 of Fig. 3;

Fig. 3 is a cross sectional view in the direction of the arrows on the line 3—3 of Fig. 2;

Fig. 4 is an end view partially in section showing the manner in which my improved package opener may be used to open a package; and

Fig. 5 is an end elevation showing the manner in which a razor blade may be inserted or removed.

My improved package opener comprises a guide head for guiding the device in opening a package, a handle portion which may be gripped by the operator, and a cutting implement adjustably mounted in the handle portion so as to project between the portions of the guide head when in use.

The guide head comprises a pair of diverging guide plates 10 and 11 of similar construction tapering in width from the trailing edge to the leading edge thereof and disposed at an angle to each other. In using my device, the respective

guide plates are adapted to rest on adjacent panels of the package with the meeting edges thereof resting on the corner of the package which is to be severed. Since, in the average package, the top and bottom are disposed at right angles to the sides, I prefer to dispose the respective plates 10 and 11 at an angle of 90 degrees to each other, as shown. Each of the plates are preferably of lesser width at the leading edge than at the trailing edge so as to serve more or less as an indicator or an arrowhead to indicate to the operator the direction in which the device is to be shifted when in use.

The handle portion which is indicated generally at 12 comprises a pair of proximately positioned substantially parallel rectangular plates 14 and 15 which are preferably formed integral with the respective guide plates 10 and 11. At their upper ends the guide plates are joined by a substantially cylindrical tubular portion 16 which is preferably formed integral with the respective plates. The tubular portion 16 serves as a comfortable hand rest for the operator and also serves as a spring hinge to facilitate the spreading of the plates 14 and 15 when it is desired to insert or remove a razor blade therefrom in the manner shown in Fig. 5. The handle portion is provided with guide, adjusting, and clearance slots for the cutting implement as will be later explained.

The cutting implement employed in my package opener preferably comprises a single edged razor blade as indicated at 17 consisting of a blade portion 18 made of suitable tool steel with a cutting edge formed along the lower end thereof and having a backing strip 19 suitably attached to the opposite edge thereof. The single edge razor blade illustrated and described herein is of one well-known conventional type and the blade portion thereof is provided with a central aperture as indicated at 20.

When assembled the blade is inserted between the two plates 14 and 15 of the handle portion and is disposed at an angle as shown with one corner and the adjacent portion of the cutting edge projecting between the two guide plates 10 and 11. To hold the blade at the proper position and so as to guide the adjustment thereof I provide each of the plates 14 and 15 with an angularly disposed guide slot 21 of sufficient width to accommodate the backing strip 19. As shown most clearly in Fig. 1 the slots 21 slant upwardly from the trailing edge towards the leading edge of the handle. Thus it will be seen that when the blade is inserted in the handle portion with the backing strip 19 disposed in the slots 21 and

with the blade depending downwardly, the position of the razor can be adjusted so that the one corner and a portion of the cutting edge projects outwardly between the two guide plates 10 and 11 as shown. The slots 21 are of sufficient length so as to permit longitudinal adjustment of the razor from a position with a substantial portion of the blade exposed between the guide plates as shown in full lines in Fig. 2 to a position with the blade completely retracted and concealed by the handle portion as shown in dotted lines in Fig. 2. For this purpose the slots 21 are positioned near the bottom of the plates 14 and 15 at one end and extend into the tubular portion 16 at the opposite end.

So as to permit the razor to be completely retracted with the blade encased in the handle portion I provide a clearance slot 22 at the top of the tubular portion, the slot being large enough to accommodate the backing strip 19 in the manner shown in dotted lines in Fig. 2. In order to hold the blade in adjusted position I provide adjusting slots 23 in the two plates 14 and 15. The adjusting slots are disposed beneath the guide slots 21, are parallel thereto, and may be of smaller size as shown. A small bolt 24 extends through the slots 23 and through the opening 20 formed in the razor blade and a readily adjustable nut such as the knurled nut 25 has threading engagement with the end thereof.

In assembling my improved package opener the handle plates 14 and 15 are spread apart and a single edged razor blade of the type shown is inserted between the plates as shown in Fig. 5 until the backing strip is disposed in the guide slots 21. The bolt 24 is then inserted through the guide slots 23 and the aperture 20 in the blade, and the nut 25 is attached thereto. The razor is then adjusted to the desired position and the screw 25 is tightened.

In Fig. 4 I have illustrated the manner of using my package opener. It is placed over one of the corners of the package with one guide plate disposed on the top panel and the other guide plate disposed on a side panel and with the razor blade 18 protruding diagonally into the corner of the package. The instrument is then drawn forwardly in the direction of the more narrow ends of the guide plates with the result that the blade severs the top from the remainder of the package. The package opener may be used in opening packages made of cardboard, pressed paper, fiber, light wood and similar materials and it may be used not only in removing the top panel but also in removing side or bottom panels.

The handle and guide head portion of the package opener may be made of any desired

material and may be made in one piece or of several pieces connected together. However, I prefer to form the device of a single sheet of metal such as steel fashioned into the shape shown. The razor blade illustrated is one conventional type of single edge blade having a blade portion made of steel and a backing strip made of some suitable metal attached thereto.

It will be appreciated from the foregoing description of my invention that I have provided an improved package opener of simple construction which is easy to operate and will cause a minimum of damage to the contents of the package and which employs as the cutting implement a razor blade, preferably a single edge blade having a backing strip.

It should be understood to course that modifications may be made in the illustrated and described embodiment of my invention without departing from the invention as set forth in the accompanying claim.

I claim:

A package opener comprising a handle portion formed of two parallel proximately positioned metallic plates integrally connected at their upper edges by means of a resilient tubular portion which permits the plates to be spread apart, a guide head comprising two diverging guide plates integrally connected to the lower edges of the plates of the handle portion, and a single edge razor blade formed with a backing strip disposed at an angle between the two plates of the handle portion with a portion of the cutting edge depending downwardly and exposed at the central point between the guide plates when in operative position, and means for releasably holding the razor blade in position and providing for the adjustment thereof comprising an aperture in the razor blade, a pair of angularly disposed slots in the respective plates of the handle portion, means extending through the aperture and said slots for shifting the razor blade along the slots and for retaining it in adjusted position, and a second pair of angularly disposed slots formed in the respective plates of the handle portion and parallel to the first-mentioned pair of slots for accommodating the backing strip of the razor blade, said last-mentioned pair of slots being of sufficient length to permit of adjustment of the razor blade, and the tubular portion of the handle of the package opener being provided with an opening at the top thereof positioned in the line of projection of the second-mentioned pair of slots for accommodating the upper corner of the razor blade so as to permit the cutting edge to be completely encased in the handle when in inoperative position.

HAMILTON GRINNELL DISBROW.
